UNITED STATES PATENT OFFICE

2,439,855

RESPIRATOR

James C. Mortensen, Princeton, Ill.

Application July 16, 1946, Serial No. 683,900

5 Claims. (Cl. 128—146)

1

My invention relates to respirators and more particularly to respirators for people suffering from hay fever and for people working in an atmosphere laden with dust or charged with fumes.

The object of my invention is to provide a respirator held in position without the use of a band surrounding the head, whereby the discomfort caused by perspiration and dust is practically eliminated.

A further object of my invention is to provide a respirator equipped with exchangeable nose pieces and a mouth piece, permitting the user of the respirator to smoke a cigarette while wearing the respirator.

Another object of my invention is to provide a respirator having a filter box adapted to receive specially treated filters exchangeably therein.

An additional object of my invention is to provide a respirator being adapted to receive exchangeably light sterile wool or cotton pads on the bottom of the nose pieces to absorb any occurring mucus flow.

Other objects of my invention may appear in the following specification describing my invention with reference to the accompanying drawing illustrating a preferred embodiment of my invention.

It is however to be understood that my invention is not to be limited or restricted to the exact construction and combination of parts described in the specification and shown in the drawing, but that such changes and modifications can be made, which fall within the scope of the claims appended hereto.

In the drawing

Figure 1 is a front view of a respirator according to my invention,

Figure 2 is a side view of Figure 1,

Figure 3 is a perspective view of a filter box used in connection with the respirator according to my invention,

Figure 4 is a nose piece used on the respirator according to my invention, and

Figure 5 is a filter cut to be used in the filter box shown in Figure 3.

Referring now to the drawing in detail the respirator forming the subject matter of my invention has a body 10 formed of any suitable plastic material of any shade and color. The body 10 has a substantially convex front and a substantially concave back. On the back a mouth piece 11 is formed adapted to be gripped and held by and between the lips or teeth of a user.

The mouth piece 11 is provided with a bore 12 ending in a cavity in the body 10 adapted to re-

2

ceive and hold a filter box 13 snugly but removably therein.

The top surface of the body 10 is arranged to slope rearwardly and has two counterbored holes 14 therein, which end also in the filter box cavity in the body.

In each of the counterbores of the holes 14 a nose piece 15 is located. These nose pieces are also made from plastic material and fit snugly but removably into the counterbores. Each nose piece is shaped substantially cylindrical and has a bore 16 therein, but the upper end of each nose piece is narrowed down by being rounded off as shown at 17. The nose pieces 15 do not extend all the way down to the bottom of the counterbores and the spaces between the lower ends of the nose pieces and the bottoms of the counterbores are filled preferably with loosely packed sterilized cotton or lamb's wool, as indicated at 18.

The filter box 13 has a rectangular top wall 19, a rectangular bottom wall 20, a rectangular back wall 21 and two rectangular end walls 22. In the longitudinal center of the filter box 13 a block 23 is formed extending transversely of the box from the front to the back.

This block 23 is provided with a centrally located hole 24 therein, extending from the front to the back of the block, and in the rear end of the hole 24 a finely perforated disk 25 is securely but removably inserted.

The bore 12 in the mouth piece 11 is arranged coaxially with the hole 24 and the perforated disk 25 therein. The hole 24 is of cigarette size, that means a cigarette 26 can be inserted in the hole 24 and can be smoked by the user of the respirator according to my invention.

In the top wall 19 of the filter box 13 two holes 27 are provided and located, so that they will coincide with the lower ends of the counterbored holes 14 in the body, when the filter box is placed in the body.

A specially cut filter 28 is illustrated in Figure 5. Such filters can be made from filter paper or other suitable material and can be folded to fit into the filter box. They can be treated with special chemicals, if the respirator is to be used in a fume laden atmosphere.

The respirator according to my invention can be made in several sizes, for instance for adults, medium size and for children, and the size of the nose pieces can be made in accordance with the size of the respirator.

The respirator, as described and shown, can be held by a light grip with the teeth or the lips

and does not require the use of a band or the like surrounding the head of a user.

The cotton or lamb's wool in the counterbores will absorb any flowing mucus and can easily be removed and replaced.

Having described my invention, I claim as new and desire to secure by Letters Patent:

1. A respirator having a body including a mouth piece integrally formed with the body, and having a bore therein communicating with a cavity in the body, and a pair of nose pieces extending upwardly from the body and having bores therein communicating with said cavity, and a filter box adapted to be removably inserted in the cavity, and having two openings in its top communicating forwardly with the atmosphere, the body having two counterbored holes therein communicating with the holes in the filter box and the nose pieces being removably inserted in the counterbores.

2. A respirator having a body including a mouth piece integrally formed with the body, and having a bore therein communicating with a cavity in the body, and a pair of nose pieces extending upwardly from the body and having bores therein communicating with said cavity, and a filter box adapted to be removably inserted in the cavity, and having two openings in its top communicating forwardly with the atmosphere, the body having two counterbored holes therein communicating with the holes in the filter box and the nose pieces being removably inserted in the counterbores, and sterile, mucus absorbing material removably and loosely packed in the counterbores underneath the nose pieces.

3. A respirator having a body including a mouth piece integrally formed with the body, and having a bore therein communicating with a cavity in the body, and a pair of nose pieces extending upwardly from the body and having bores therein communicating with said cavity, and a filter box adapted to be removably inserted in the cavity, and having two openings in its top communicating forwardly with the atmosphere, the body having two counterbored holes therein communicating with the holes in the filter box and the nose pieces being removably inserted in the counterbores, the central portion of the filter box being formed like a block and having a bore therein extending from front to back, adapted

to receive and hold a cigarette, and communicating with the bore in the mouthpiece.

4. A respirator having a body including a mouth piece integrally formed with the body, and having a bore therein communicating with a cavity in the body, and a pair of nose pieces extending upwardly from the body and having bores therein communicating with said cavity, and a filter box adapted to be removably inserted in the cavity, and having two openings in its top communicating forwardly with the atmosphere, the body having two counterbored holes therein communicating with the holes in the filter box and the nose pieces being removably inserted in the counterbores, the central portion of the filter box being formed like a block and having a bore therein extending from front to back, adapted to receive and hold a cigarette, and communicating with the bore in the mouthpiece, and a perforated disk removably arranged in the rear portion of the bore in the block-like central portion of the filter box.

5. A respirator having a body including a mouth piece integrally formed with the body, and having a bore therein communicating with a cavity in the body, and a pair of nose pieces extending upwardly from the body and having bores therein communicating with said cavity, and a filter box adapted to be removably inserted in the cavity, and having two openings in its top communicating forwardly with the atmosphere, the body having two counterbored holes therein communicating with the holes in the filter box and the nose pieces being removably inserted in the counterbores, and sterile, mucus absorbing material removably and loosely packed in the counterbores underneath the nose pieces, and a filter material removably inserted in the filter box.
